UNITED STATES PATENT OFFICE

109,418

DESIGN FOR A WALL TELEPHONE

Herbert F. Obergfell, River Forest, Ill., assignor to Associated Electric Laboratories, Inc., Chicago, Ill., a corporation of Delaware

Application September 22, 1937, Serial No. 71,715

Term of patent 14 years

To all whom it may concern:

Be it known that I, Herbert F. Obergfell, a citizen of the United States of America, residing at River Forest, Cook County, Illinois, have invented a new, original, and ornamental Design for a Wall Telephone, of which the following is a specification, reference being had to the accompanying drawing forming a part thereof.

I claim:

The ornamental design for a wall telephone as shown.

HERBERT F. OBERGFELL.
